FURNACE

Marlin Warren, Milwaukee, Wis.

Application May 26, 1934, Serial No. 727,639

8 Claims. (Cl. 126—101)

This invention appertains to furnaces, and more particularly to novel means for obtaining a maximum amount of benefit from the fuel utilized in the heating of homes and other buildings.

It is well recognized that the available energy in various type of commercial fuel is not used to its greatest advantage, and that a large proportion of the heat units are wasted. This is particularly true of the so-called "hot air" furnace, which, in some respects, is particularly desirable in home heating, as it allows the continuous supply of fresh heated air to the rooms.

Oil is a very desirable form of fuel, but as far as I am aware, oil burners have not been successfully used in hot air furnaces, due to the fact that the volume of air heated is small in comparison to the amount of heat generated and the amount of fuel used.

Therefore, one of the salient objects of my invention is the provision of a hot air furnace embodying novel means for heating the air flowing through the furnace, through the medium of water circulated around the combustion chamber, the air flowing around hot water pipes located in the path of the air stream, which communicate with the circulating pipe.

Another salient object of my invention is to provide a hot air furnace utilizing an oil burner, with novel means for obtaining a maximum amount of heat therefrom, by the use of hot water through banks of pipes disposed in the hot air box of the furnace.

A further object of my invention is the provision of novel means for circulating the water through the water jacket, or boiler, so as to insure a continuous flow of heated water through the banks of water pipes located in the hot air box, a water arch being disposed directly within the combustion chamber having communication at its upper and lower ends with the water in the jacket.

A further object of my invention is the provision of novel means including a blower for initially forcing the incoming air around the hot water casing, or boiler, thence around the banks of hot water pipes located in the hot air box, and finally subjecting the air, prior to its flow into the hot air distributing pipes, to the superheating influence of a radiator consisting of smoke flues utilized for connecting the combustion chamber with the smoke outlet pipe.

A further object of my invention is the provision of means for causing a triple flow of air through the furnace to insure the proper raising

of the temperature thereof, the air being forced into the bottom of the furnace between the jacket and the outer shell of the water compartment, up the sides of the furnace, and thence into the inner shell, or hot air box, where the air again travels up and out to the air distributing pipes, the hot air box having means therein for humidifying the air.

A further object of my invention is the provision of a vertical smoke flue, or column, leading directly through the water compartment, or boiler, from the combustion chamber, so that the water in said compartment, or boiler, will be effectively heated by said flue.

A still further object of my invention is the provision of an improved oil burning hot air furnace of the above character, which will be durable and efficient in use, one that will be simple and easy to manufacture, and one which will be of a compact and rugged construction.

With these and other objects in view, the invention consists in the novel construction, arrangement, and formation of parts, as will be hereinafter more specifically described, claimed, and illustrated in the accompanying drawings, in which drawings:

Figure 1 is a vertical section through my improved furnace.

Figure 2 is a horizontal section through the furnace, taken on the line 2—2 of Figure 1, looking in the direction of the arrows.

Figure 3 is a vertical section taken at right angles to Figure 1, and substantially on the line 3—3 of Figure 1, looking in the direction of the arrows.

Referring to the drawings in detail, wherein similar reference characters designate corresponding parts throughout the several views, the letter A generally indicates my improved furnace, which comprises an inner main casing 5, and which forms a water compartment, or boiler.

This casing 5 may include spaced longitudinal extending side walls 6, end walls 1, and top and bottom walls 8 and 8'. The casing 5 is surrounded by an outer jacket 10 formed of sheet metal, or the like, built on a desired type of base and surrounded by a curbing 9. The jacket is disposed in spaced relation to the casing, and the space between the jacket and the casing constitutes an air conduit 19, as will be later set forth.

Arranged within the casing 5 is a combustion chamber 11. This combustion chamber 11 is of a narrower width than the casing, and of a less

- length than said casing, and has communicating with its front end a vertically extending flue 12 which extends through the water compartment and out the top wall 8 of the casing. A 5 hot air dome 13 extends over the casing and shell, and has communicating therewith the hot air distributing pipes 14, which lead to the various rooms of the building to be heated.
- The forward end of the combustion chamber 10 11 is provided with an inlet mouth 15 which opens out through the front of the furnace, and this inlet mouth receives the combustion and discharge tube 16 of an oil burner 17. The oil burner 17 can be of any preferred type or make.
- 15 Arranged within the casing, in spaced relation to the side and end walls thereof, is a relatively large hot air box 18, which forms the inner shell of the casing 5. This hot air box 18 depends from the top wall 8 of the casing, and opens out 20 through said top wall into the hot air dome 13. The lower end of the hot air box terminates above the combustion chamber 11, for a purpose which will be later set forth.
- Extending into the opposite sides of the hot 25 air box 18 are relatively wide hot air inlet pipes, or flues, 20, and these inlet flues communicate with the opposite sides of the hot air conduit 19 midway its ends. A fresh air inlet opening is provided at the extreme lower end of the 30 air conduit 19, preferably at the rear thereof, and the air is forced therein by means of a blower 35, which can be of any preferred character or make.
- From the description so far, it can be seen that 35 the cold fresh air enters from the bottom of the furnace and flows up around the outer face of the boiler, or casing, and is initially heated by the hot water therein. The air then enters the conduits 20 and flows up the hot air box 18.
- 40 Thus, the air circulates three times through the furnace.
- After the air leaves the hot air box, the same flows into the dome, and thence into the hot air distributing pipes.
- 45 The rear part of the dome 13 supports a header 21 which has communicating therewith the smoke outlet pipe 22. This pipe 22 leads to the chimney, and a damper 23 can be arranged in said pipe. As heretofore stated, the vertical 50 column, or flue, 12 of the combustion chamber extends through the top wall 8 of the casing, and this extended end of the column, or flue, 12 has communicating therewith a plurality of flue pipes 24, which open into the header 21. Thus, 55 the products of combustion flow through a plurality of flue pipes located in the dome, and the same constitutes a radiator, so that the air, prior to its exit from the furnace, is subjected to a final, or superheating, process.
- 60 In accordance with my invention, I fill the casing 5 with water, and thus this water entirely surrounds the combustion chamber 11 with its vertical flue, or column, 12, and the hot air box 18. The casing can be filled with water through 65 the medium of a water pipe 25, which can be connected to any source of water supply, such as a city main. A control valve 26 is interposed in the length of this pipe for governing the flow of water to the casing.
- 70 Various control means can be provided for the furnace, and thus the same can be provided with a safety valve 27, a sight glass 28, and a thermometer 29.
- In order to insure the thorough heating of 75 the water, and the proper circulation thereof,

I arrange a water arch 30 in the combustion chamber. This water arch 30 consists of a plurality of water pipes 31, and the same are disposed in parallel relation and at an angle to the horizontal. The extreme lower ends of the tubes, or pipes, 31 extend through the rear wall of the combustion chamber and communicate with the lower part of the interior of the casing. The forward upper ends of the tubes, or pipes, 31 are extended for a considerable distance in the smoke flue, or pipe, 12, and the same are finally passed through one wall of this pipe, or flue, for communication with the upper part of the interior of the casing.

In order to protect the water arch from the 15 direct flame, the outlet end of the oil burner is surrounded with a guard 32 located directly below the water arch. Extending longitudinally through the hot air box 18 are horizontally disposed rows, or banks, of hot water pipes, or 20 tubes, 33. These hot water pipes extend through the opposite end walls of the hot air box, and communicate with the interior of the casing. The pipes of the rows of pipes are staggeredly related to one another, so as to insure proper 25 flow of air around the same.

In use of my improved furnace, the temperature of the water is quickly raised by the oil burner, and this is enhanced due to the water pipes located directly in the combustion chamber. Obviously, as the water is heated in the pipes 31, the same rises and exits into the upper 30 part of the casing. This hot water will circulate through the water tubes 33 located in the hot air box, and as the water in these tubes becomes 35 cold by the flow of air thereabout, the same is re-heated by the tubes 31.

The air flow through the hot air box has its temperature quickly raised by the same flowing past the banks, or rows, of pipes 33, and obviously 40 the walls of the box itself are heated by the hot water thereabout. As the heated air leaves the hot air box, the same flows past the smoke pipes 24, which tends to increase the temperature of the air.

From the foregoing description, it can be seen 45 that I have provided novel means for effectively utilizing an oil burner in conjunction with a hot air furnace, and for insuring the proper heating of the air.

I also prefer to arrange in the lower part of 50 the hot air box a humidifying device. The desired amount of water is admitted into the box by a float-controlled valve 36. Obviously, the air sweeping over the water is humidified there- 55 by.

My device is so arranged and constructed that the same can be utilized during the summer season for cooling air flowing therethrough. The device is, therefore, susceptible as a heating medium in the winter season and a cooling medium 60 in the summer season for a home.

Changes in details may be made without departing from the spirit or the scope of my invention, but what I claim as new is:—

1. A hot air furnace comprising a water casing, a hot air jacket surrounding the sides and bottom of the water casing, said jacket having a cold air inlet at its lower end, a fuel combustion chamber in the lower part of said casing, 70 a hot air box disposed in the casing above the combustion chamber having tubes extending therethrough communicating with the water in said casing, a hot air dome arranged above the casing for receiving the hot air from the box, 75

the box having air inlets connecting the lower end thereof with the space between the jacket and the casing intermediate the ends of the furnace, and hot air distributing pipes communicating with the dome.

5. A hot air furnace comprising a water receiving casing, a jacket disposed entirely about the sides and bottom wall of the casing, defining a hot air conduit thereabout, the lower end of the conduit being provided with a cold air inlet, a fuel combustion chamber in the casing, a hot air box arranged in said casing above the combustion chamber for the circulation of water thereabout, a hot air dome carried by the casing 10 communicating with the upper end of the box, the opposite sides of the hot air box being provided with inlets communicating with the hot air conduit intermediate the ends thereof, a plurality of hot air distributing pipes communicating 15 with the dome, and an air blower communicating with the inlet of the conduit, said blower forcing the air up the conduit around the bottom and sides of the casing, thence into the inlets of the hot air box, and up through the 20 box into the dome.

3. A hot air furnace comprising a water receiving casing, a jacket disposed entirely about the sides and bottom wall of the casing, defining a hot air conduit thereabout, the lower end of the conduit being provided with a cold air inlet, a fuel combustion chamber in the casing, a hot air box arranged in said casing above the combustion chamber for the circulation of water thereabout, a hot air dome carried by the 25 casing communicating with the upper end of the box, the opposite sides of the hot air box being provided with inlets communicating with the hot air conduit intermediate the ends thereof, a plurality of hot air distributing pipes communicating 30 with the dome, an air blower communicating with the inlet of the conduit, said blower forcing the air up the conduit around the bottom and sides of the casing, thence into the inlets of the hot air box, and up through the 35 box into the dome, and an air humidifying device arranged in the hot air box directly below said air inlets.

4. A hot air furnace comprising a water casing, a fuel combustion chamber in said casing, a hot air box disposed in the casing above the combustion chamber having tubes extending therethrough communicating with the water in said casing, a hot air dome arranged above the casing for receiving the hot air from the box, air inlets communicating with the lower end of the box, and hot air distributing pipes communicating 40 with the dome.

5. A hot air furnace comprising a casing for the reception of water, a fuel combustion chamber arranged in said casing, a hot air box arranged in said casing above the combustion chamber for the circulation of water thereabout, a hot air dome carried by the casing communicating with the upper end of the box, air inlet 45 pipes communicating with the lower end of the box, a smoke outlet pipe, and a plurality of

flues disposed in the hot air dome above the hot air box connecting the combustion chamber with the smoke pipe.

6. A hot air furnace comprising a vertical casing for the reception of water, a combustion chamber arranged within the casing, a hot air box disposed in the casing, a hot air dome carried by the casing communicating with the upper end of the box, a plurality of air distributing pipes communicating with the dome, oppositely directed air inlet pipes communicating with the power part of the box, a plurality of hot water conducting pipes disposed in the hot air box having their opposite ends communicating with the interior of the casing, a smoke 15 pipe, and a plurality of flues disposed within the hot air dome above the box communicating with the combustion chamber and the smoke pipe, constituting a radiator for superheating the air prior to the entrance thereof into the 20 air distributing pipes.

7. A hot air furnace comprising a vertical casing for the reception of water, a combustion chamber arranged within the casing, a hot air box disposed in the casing, a hot air dome carried by the casing communicating with the upper end of the box, a plurality of air distributing pipes communicating with the dome, oppositely directed air inlet pipes communicating with the lower part of the box, a plurality of hot water 30 conducting pipes disposed in the hot air box having their opposite ends communicating with the interior of the casing, a smoke pipe, a plurality of flues disposed within the hot air dome above the box communicating with the combustion chamber and the smoke pipe, and a water arch in said combustion chamber including a plurality of inclined water conducting tubes having their upper and lower ends in communication with the interior of the casing.

8. An oil burning hot air furnace comprising a casing for the reception of water, a fire box disposed in the casing having an inlet opening out through the furnace for the reception of the inlet end of an oil burner, a vertically disposed 45 column connected with the fire box and extending through the casing and the water therein and out of the top wall of the casing, a dome carried by the top wall of the casing receiving the closed upper end of the column, a hot air 50 box disposed in the casing above the fire box and having communication with the dome, a plurality of hot air distributing pipes communicating with the dome, a plurality of hot water 55 conducting pipes disposed in the hot air box having communication at their opposite ends with the interior of the casing, a smoke pipe, a plurality of flues constituting a radiator, arranged in the dome connecting the column with the smoke pipe, and a plurality of water conducting pipes disposed in the fire box arranged at an incline to the horizontal with the opposite ends of said pipes communicating with the interior of the casing.

MARLIN WARREN. 65
